(57) **CLAIM**

The ornamental design for an LED light with clamp assembly for a lawn tool, as shown and described.

DESCRIPTION

FIG. 1 is a front perspective view of an LED light with clamp assembly for a lawn tool shown in use condition, showing my new design;

FIG. 2 is an enlarged, front elevation view of the LED light with clamp assembly for a lawn tool of FIG. 1;

FIG. 3 is a rear elevation view thereof;

FIG. 4 left side elevation view thereof;

FIG. 5 is a right side elevation view thereof;

FIG. 6 is a top plan view thereof; and,

FIG. 7 is a bottom plan view thereof.

The broken lines illustrating an LED light with clamp assembly for a lawn tool in FIG. 1 show environmental structures and form no part of the claimed design.
